UNITED STATES PATENT OFFICE.

JAMES R. CARDWELL, OF CHICAGO, ILLINOIS.

RAILWAY-CAR TRUCK.

Application filed August 31, 1927. Serial No. 216,512.

The invention relates to railway car trucks of the type in which the truck bolster is yieldingly supported in part by friction elements.

5 The object of the invention is to relieve, in great measure, the side frame of the truck from the spreading action of the friction elements; and it consists in a structure as hereinafter described and as illustrated in the accompanying drawings, in which

Fig. 1 is a side elevation of the car truck embodying the invention;

Fig. 2 is a detail vertical longitudinal section of the truck side frame, some parts being shown in elevation;

Fig. 3 is a detail section on the line 3—3 of Fig. 1;

Fig. 4 are views in perspective of the several movable friction elements of the device; and

20 Fig. 5 is a view in perspective of the tray containing such movable elements.

The device is, in many of its features, like that forming the subject of my application Ser. No. 216,511 filed concurrently with this; 25 the essential difference being that in the present instance the stationary wedging elements are carried by or, as shown, incorporated into a tray of sufficient strength to sustain all or much of the lateral stresses transmitted 30 through the movable wedging elements.

In the accompanying drawings there is shown at 10 the side frame, in arch form, of a car truck, and at 11, 11, a pair of supporting wheels. The truck bolster of the car is shown 35 at 12, and, as usual, each of its ends is supported by springs 13, the bolster having vertical movement between a pair of columns or guide bars 14, 15, which form parts of the side frame of the truck.

40 In practice heretofore prevailing these springs have been seated directly upon the lower arch 16 of the truck, which connects the lower ends of the columns 14, 15. The present invention provides for the introduction between these springs and the member 45 16 of a series of wedging elements.

Such elements comprise a tray 17, of suitable form to fit between the columns 14, 15, and to rest upon the member 16, being held 50 in place as by means of downwardly projecting flanges 18, which embrace the side margins of this member.

The inner face of the end walls of the tray are inclined, as shown at 19, to form wedge 55 faces. Seated within the tray are a pair of

wedge blocks or bars 20, 21, which, in cross-section, take the form of inverted truncated cones. These elements 20, 21, form the seats for the lower ends of the springs 13.

A pair of blocks 22, 23, triangular in cross-section, and preferably equilateral, are interposed between the members 20, 21, bearing, respectively, against the inner inclined face of each. Interposed between, and bearing directly upon the elements 22, 23, is a double faced wedge element 24, having an upwardly projecting stem 25, which extends into a pocket 26 formed in a rib 27 depending from the bolster 12. A spring 28, here shown as being in leaf form, is interposed between the upper end of the stem 25 and the inner end of the pocket 26.

In the normal position of the parts, as shown in Fig. 2, the flattened shorter or end faces of the elements 20, 21, are seated upon the bottom of the tray 17, their outer inclined faces resting against the inclined faces 19 of the tray; the wedge elements 22, 23, are seated upon the bottom of the tray, each engaging an inclined face of one of the elements 20, 21; the wedge element 24 is seated against the adjacent faces of the elements 22, 23, and the spring 28 urges all of these wedge elements into close contact.

Any slight shocks in vertical direction will cause the relative approach of the members 12 and 16, correspondingly compressing the springs 13. Shocks which are of sufficient force to completely compress the spring 28 move the element 25 downwardly, thereby spreading the blocks 22, 23, apart and forcing the blocks 20, 21, upwardly, by a wedging action, against the resistance of the springs 13. When the member 24 engages the bottom of the tray 17, further downward movement of the bolster 12 is arrested. The parts are so proportioned that the possible downward movement of the bolster is within the compressive limit of the springs 13, thereby relieving them from full compression, and hence greatly reducing the tendency to impart to them a permanent set.

The tray 17 may fit snugly between the columns 14, 15, but inasmuch as in the manufacture of devices of this kind machining is 105 to be avoided, it becomes impracticable to insure positive engagement of the ends of the tray with the columns. The tray is made of sufficient strength to resist lateral stresses imposed upon it by the action of the wedges. 110

Upon the recoil the springs 15 return all of the movable wedging elements to their normal position, as shown in Fig. 2.

The stresses of the more severe shocks are largely absorbed by the friction between the several wedge faces and between the blocks 22, 23, and the bottom of the tray. The lateral stresses due to the spreading action of the central member 24 are resisted by the side and bottom webs of the tray 17.

10 The described embodiment of the invention is simple and efficient, but it may take various other forms, as for adapting it for use in connection with other types of truck frames.

15 I claim as my invention:

1. In a car truck, an end frame, a bolster, springs for supporting the bolster, a pair of wedge blocks having backwardly and upwardly inclined wedging faces carried by the frame, means connecting such blocks together to resist spreading stresses, double faced wedging elements engaging such faces and forming seats for the springs, a pair of 20 triangular wedge blocks each engaging a face of the last named blocks, and a spreading wedge interposed between the triangular blocks and having a stem engageable by the bolster.

25 2. In a car truck, in combination, a frame having columns and a lower arch, a bolster

slidably engaging the columns, a tray supported by the arch and having upwardly and outwardly inclined wedging faces adjacent to its ends, a pair of double faced wedge 35 blocks engaging the wedging faces of the tray, a pair of triangular wedge blocks seated in the tray and engaging respectively the first named blocks, a double faced wedging element interposed between the triangular 40 blocks and having a stem engageable by the bolster, and springs reacting between the bolster and the first named blocks.

3. In a car truck, an end frame, a bolster, springs for supporting the bolster, outwardly and upwardly inclined wedging faces carried by the frame, double faced wedging elements engaging such faces and forming seats for the springs, a pair of triangular wedge blocks each engaging a face of the first 50 named blocks, and a spreading wedge interposed between the triangular blocks and having a stem engageable by the bolster, and a spring interposed between the stem and the bolster.

4. A tray for containing a system of wedging elements in a railway car truck and having upwardly and outwardly inclined wedging faces.

In testimony whereof I affix my signature.

JAMES R. CARDWELL.
